ARTICLE OF LUGGAGE

Dorothy A. Russell, New York, N. Y.

Application April 8, 1943, Serial No. 482,251

3 Claims. (Cl. 190—43)

This invention relates to a new article of luggage, and has for its principal object the provision of a novel, light-weight garment-carrying bag which is simple and inexpensive in construction and supports the garments without causing the same to become wrinkled. Another object of the invention is to provide an improved, light-weight case which eliminates slide fasteners and other fastening elements which frequently get out of order.

The garment-carrying case of the present invention is one designed to be extended to its full length when open, means being provided at one end thereof for hanging the case on the wall. At the same end of the case, there are provided means for removably supporting a plurality of garment hangers which receive and support the body garments such as suits and overcoats. The body garments may be inserted within the case while thus hanging on the wall, or it may be opened flat on a horizontal surface and the garments inserted and properly smoothed out before the case is closed.

One particularly novel feature in the present invention resides in the provision of a removable cover section for the inner surface of the case. The case has the usual end walls or gussets, and opposed, upper longitudinal marginal walls when the case is open, the inner edges of these latter walls and the opposed marginal edges of the slideable cover section having complementary male and female portions forming slideways. This provides, when the cover section is closed, a dust-proof, substantially water-proof case for the garments, and a further novel feature, in one embodiment of the invention, resides in the provision of the handle elements at opposite ends of this elongated inner cover section. This arrangement gives the bag a better sense of balance than the usual run of bags.

The improved article of luggage of the present invention is substantially frameless in the sense that metal frames, plywood side and end walls, and the like, are eliminated. The improved carrying case has only enough framework to preserve the general contour of the bag when the same is fully or even partially packed, without, however, adding any measure of weight. In this connection, the luggage-carrying device is particularly useful for members of the air force who are required to travel with a minimum weight. Accordingly, another object of the present invention resides in the provision of a case which, while substantially flexible in character, nevertheless retains its shape even when only partially packed,

and preserves the original condition of the garments inserted thereinto even after a considerable time of travel.

Yet another important object of the present invention resides in the provision of a novel garment-carrying case which, when not in use for carrying purposes, may serve as a small portable wardrobe closet. In this connection, the case when lying flat and in fully extended position has upper and lower walls of the same length and other dimensions, and side and end-walls of sufficient depth to accommodate a number of body garments, and perhaps a heavy overcoat. This upper wall, which becomes the outer wall when the entire structure is hung as from a hook on the wall, comprises relatively narrow, longitudinally-disposed fixed sections secured along opposite sides of the bag. The removable cover section is supported along the opposed inner marginal edges of these fixed sections by a novel slideway arrangement comprising substantially C shaped trackways, and complementary beaded edges which are received within the trackways. This construction is such as to permit the slideable cover to be moved into and out of covering relationship with almost the same ease as a window shade is moved up and down.

Another important object of the present invention resides in the provision of a bag of a generally flexible character wherein the main frame element is the removable sliding cover previously referred to. The bag, of course, is provided with the usual stiffening elements at opposite ends thereof which give it shape, but the primary frame device is the slide itself which converts an otherwise substantially non-rigid bag into a fairly rigid one, without, however, increasing the weight materially.

Other novel features of the present invention will be hereinafter pointed out, or will become apparent as the specification proceeds.

In the drawings:

Fig. 1 is a perspective view of one embodiment of the present invention, the view showing the article of luggage in closed position.

Fig. 2 is also a perspective view showing the article in open position.

Fig. 3 is a broken section taken on line 3—3 of Fig. 5.

Fig. 4 is a broken section taken on line 4—4 of Fig. 2.

Fig. 5 is a broken section taken on line 5—5 of Fig. 2.

Fig. 6 shows a plan view of a modified form of the invention in open position.

Fig. 7 is a broken section taken on line 7—7 of Fig. 6.

Fig. 8 is a broken section taken on line 8—8 of Fig. 6.

Fig. 9 is an enlarged perspective detail view.

Fig. 10 is an enlarged detail view, partially in section.

Fig. 11 is a broken plan view of a portion of the device.

Fig. 12 is a perspective view of one form of the invention in closed position.

When in open position, the main body section of the luggage-carrying device of the present invention is formed with a lower wall 10, which may comprise one continuous piece of substantially flexible material, such piece forming the outer side walls of the case when in the closed position shown in Fig. 1. For convenience in description, the several walls will be named in accordance with the position they occupy when the case is in the open position. Thus, the case further includes side walls 11 and opposed end walls 12 and 13, respectively. Finally, the main body section includes opposed upper walls 14 which are relatively narrow, and which extend the full length of the case. The foregoing walls may be all formed from any suitable material, preferably of a flexible character, which may include waterproof fabric, leather, or any other material generally used for the purpose. The several walls are joined together along their marginal edges as by stitching 16, thus forming a generally box-like structure.

End wall 12 may be reinforced by a rigid strip or panel 17, and another rigid panel 18 of similar size is spaced from panel 17 by means of side wall elements 19, thus forming a generally rectangular confined area which may be used for carrying shoes and other similar articles. At the opposite end of the case, end wall 13 may be reinforced by a rigid strip or panel 20 similar to panel 17, and these several panels may be secured within the case by any means known in the luggage art. Top walls 14 are of special construction in that along their inner marginal edges, generally C shaped channel elements or slideways 22 are formed. Each slideway may include a tube 23 formed with a longitudinal slot, and in the construction shown in Fig. 4, the inner marginal edge of wall 14 covers both the outside and the inside of the tube.

The tube may be made from any suitable material, such as metal, fiber, plastic, or otherwise, and if the construction of Fig. 4 is to be used, the material forming the inner marginal edge of upper wall 14 may be simply cemented or otherwise adhesively secured to such tube. The tube 23 on each side of the case is made in three sections, two longer sections which occupy a generally vertical position when the case is closed, and an intermediate short section, which in the relation shown in Fig. 1 is at the lower end of the closed case. The approximate position of the break in the sections is shown in broken lines in Fig. 2. A sliding cover member 25 may be formed from a single continuous strip of flexible material provided with beading 26 along its opposed longitudinal edges. This beading may be formed in the usual manner by turning in the marginal edges of the material and inserting a cord or wire in the overlapped portion, and then stitching such portion to the main body of the material, as shown at 27 in Fig. 4. Each end of the cover section 25 may be reinforced by a trans-

verse strip 28, and handle elements 30 are secured at such terminals. At one end of the case, preferably at the end defined by wall 13, a flexible strip 31 is so secured as to form a plurality of loops for supporting garment hangers (not shown).

When it is desired to pack the case, the body garments, including suits, overcoats, and the like (not shown), are mounted on hangers, and such garments then placed in the open case, which then occupies the position shown in Fig. 2. Shoes and other articles may be placed in the lower compartment, and the slideable cover then inserted along its opposed marginal beaded edges in slideways 22, and the cover moved to the position shown in Fig. 2. The case may then be folded, and a hinged flap 33, having an extension portion 34, folded over the top of the case. Portion 33 is provided with an opening 36 to permit handle elements 30 to pass therethrough. Flap 33 may also have end walls 37.

The construction of the case illustrated in Figs. 6—12, inclusive, differs from that shown in Figs. 1—5 in a number of respects, and for certain purposes might be preferable. Again, in this instance, the case includes a lower wall 42, opposed end walls 43 and 44, opposed side walls 45, and narrow, longitudinally-disposed top wall sections 46. The marginal edges of these several walls are joined together, as by means of stitching 47. A shoe compartment 49 is provided adjacent to end wall 43 and may include a plurality of stiff reinforcing elements or panels 50, 51, 52 and 53. The opposite end of the case may also be reinforced by means of stiffening elements 56, 57 and 58, all of which are suitably secured adjacent to end wall 44 and the terminal of lower wall 42 and upper walls 46. In this instance, the handle elements 60 and 61 are suitably secured to stiffening elements 53 and 58, respectively, rather than to the slideable cover, as in the first embodiment. There is thus provided a relatively large elongated compartment 63 for body garments, and at one end thereof, a post 64 supports the hangers (not shown) for such body garments.

The slideable cover section 68 is likewise formed with the beading 69 along its opposed marginal edges. The core 70 may be made from flexible cord, from wire, or from any other suitable material, and the terminals of this core may be stiffened, as by a dowel 71, shown in Fig. 11. This stiffened end section aids in causing the cover section to slide more freely in its supporting C shaped channels, which will now be described. These channels 72 may again be formed from tubular member 73 having slot 74 therein, shown particularly in Fig. 9, and the inner marginal edges of the top sections 46 may cover both the outside and the inside of each tube. One method of mounting the outer terminals of each tube is shown particularly in Figs. 9 and 10. Frame member 58 is formed with a slot 76, thus leaving a narrow connecting piece 77. Tube 73 is bifurcated at its end, as shown at 78, the narrow connecting piece 77 being received within the bifurcated portion, as shown in Fig. 10, and secured therein. The covering material covers both the cross-piece 58 and the tube, as well as forming, as it does, the upper wall sections 46. This tube is again made in three sections, two of which extend along the side walls of the case when closed, and a shorter section connects these longer sections.

In order to preserve the flexibility of the case, however, there is preferably a slight space between the abutting sections, as shown particularly

at 80 in Fig. 6. Cross-piece 58 is further formed with a longitudinal channel 82 on its inner edge which may receive the upper terminal portion of cover section 68, when viewed as in Fig. 6, thus making a substantially dust-proof and waterproof closure element. The opposite terminals of the slideable cover section may likewise be strengthened, as by transverse cross-pieces 84, shown in Fig. 7. Full tabs 88 at opposite ends of the cover section aid in moving this section into and out of covering position. The presence of the dowel 71 or other stiffening elements at one or both ends of the slideable cover section greatly aid in permitting the rapid closing and opening operation, and this operation is further facilitated by manipulating the cover section if the entire case is hanging vertically, as by a hook on the wall which supports upper handle member 61. When in this hanging position, the alignment of the several C shaped trackways is preserved more effectively than is the case when the article is lying flat on a horizontal surface.

The case may be maintained in carrying position by one or more straps 90 and cooperating buckles 91. The case may further be modified by providing a handle structure 92 on the outer surface of the intermediate portion which now becomes the top wall rather than the bottom wall, as in Fig. 6. This embodiment 93 of Fig. 12 may further have an external pocket 94 for carrying accessories. The positioning of such pockets is, of course, a matter of choice, and one or more of these pockets may be disposed on the slideable cover section as well.

It will be appreciated that many changes and modifications may be made in connection with the several forms of the invention herein disclosed without departing from the spirit of the invention, as defined by the appended claims. In other words, various details of construction illustrated in Figs. 6-11, inclusive, may be embodied in a case of the general character disclosed in Figs. 1-5, and vice versa, it being understood that the case shown in Figs. 6-11 is not, strictly speaking, a separate embodiment of the invention, but merely illustrates alternate constructions of certain parts of the case which may be dictated by considerations of material, articles to be carried, and the like. For instance, flaps 33 and 34 of the embodiment shown in Fig. 1 may be used in connection with the case illustrated in Fig. 6, and likewise, the arrangement of the slideable cover section and its supporting elements, shown in Fig. 6, may be used in connection with the first form of the invention.

The longitudinal channel 82 in cross-piece 58, which receives one terminal portion of the slideable cover, forms an effective seal for the cover and prevents dust and water from getting inside the case, as was earlier pointed out. Substantially the same arrangement may be formed at the opposite end of the case, when viewed as in Fig. 7, and this may be effected by simply terminating tube 73 just short of cross-piece 53 and providing a slot in cross-piece 53 similar to the slot 82 in cross-piece 58. The length of the cover is such as to just slightly overlie the edge of

cross-piece 53 when the opposite end of the cover is seated in recess 82. The cover may then be pushed in the direction of its opposite end sufficiently to get beyond this edge and thus drop into the recess in cross-piece 52, thus providing substantially the same water-tight arrangement at each end of the case.

The structural details of the present invention have been discussed and illustrated only in connection with an article of luggage for carrying body garments. It will be appreciated, however, that the sliding cover structure may also be used in connection with other forms of containers and article-carrying devices such as hand bags, overnight cases, brief cases, and the like.

What I claim is:

1. A garment-carrying case comprising an elongated, generally rectangular body section adapted to be folded along a transverse median line, and means for retaining the case in such folded position, the body section including upper and lower walls, and side and end walls, the upper wall comprising longitudinal opposed sections on each side of the case and being formed with trackways of substantially C shaped contour, and a closure slide formed with opposed beaded edges adapted to be received in the trackways in slideable relation to close the case after the garments have been inserted therein.
2. A garment-carrying case comprising an elongated, generally rectangular body section adapted to be folded along a transverse median line, and means for retaining the case in such folded position, the body section including upper and lower walls, and side and end walls, the upper wall comprising longitudinal opposed sections on each side of the case and being formed with trackways of substantially C shaped contour, the trackways being formed in a plurality of substantially abutting sections adapted to be aligned when the case is in extended position, and a closure slide formed with opposed beaded edges adapted to be received in the trackways in slideable relation to close the case after the garments have been inserted therein, at least one terminal of such beaded edges being formed with a stiffened section to aid in moving the slide into closed position.
3. A garment-carrying case comprising an elongated, generally rectangular body section adapted to be folded along a transverse median line when carried, and to be laid flat in extended position when being packed and unpacked, the body section including upper and lower walls, and side and end walls, all of substantially flexible material and forming a garment-carrying section, the upper wall comprising longitudinally opposed sections on each side of the case and being formed with trackways of substantially C shaped contour, a closure slide formed with opposed beaded edges adapted to be received in the trackways in slideable relation to close the case after the garments have been inserted therein, transverse strengthening elements disposed at opposite ends of the case, and a garment hanger support secured at one end of the garment-carrying section.

DOROTHY A. RUSSELL.
